(57) **CLAIM**

The ornamental design for a bottle storage device as shown and described.

DESCRIPTION

FIG. 1 is a perspective view of a bottle storage device showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines shown in the Figures show portions of the bottle storage device that form no part of the claimed design.

The dot-dash broken lines shown in the FIGS. 1-7 represent the boundaries of the design and form no part thereof.

The shade lines in the Figures show contour and do not claim surface ornamentation or treatment.
